ATTORNEY.

UNITED STATES PATENT OFFICE.

CYRIL W. KING, OF OSWEGO, NEW YORK.

ELECTRIC-LIGHT FIXTURE.

1,213,384.

Specification of Letters Patent.

Patented Jan. 23, 1917.

Application filed October 1, 1913. Serial No. 792,902.

To all whom it may concern:

Be it known that I, CYRIL W. KING, a citizen of the United States of America, residing at Oswego, in the county of Oswego, in the State of New York, have invented new and useful Improvements in Electric-Light Fixtures, of which the following, taken in connection with the accompanying drawings; is a full, clear, and exact description.

This invention relates to certain improvements in supports for electric light fixtures adapted to be secured to and suspended from the ceiling or walls of a building for conduit or open wiring and refers more particularly to the connection between the tubular arm or arms through which the wires are passed to the lamps and the head for receiving and supporting such arm or arms. These heads are made in various forms for drop or wall fixtures according to the class of wiring installed—that is whether open wiring or conduit work—but in the present system of wiring most commonly employed, the connections between the tubular fixture arms and supporting head therefor are made by threading both parts and securing one part into the other after the electric wires have been drawn through the tubular arms or fixtures.

Aside from the expense of cutting the threads in or upon both parts, it is necessary to rotate the tubular arm several turns in securing it into the head which not only tends to twist the wires and strain their terminal connections with the lamp sockets but frequently strips the insulation from said wires, thereby increasing the liability of short circuits and consequent imperfect service if not actual danger from fire.

When the sections are coupled and the ends of the fixture wires are properly connected to the feed wires at the junction of the fixture with the head, the coupling and joined ends of the wires are usually inclosed within and concealed by ornamental balls or canopies of sheet metal having suitable openings through which the fixture arms are passed, the ornamental shells or fixtures being provided with suitable means for holding them in their adjusted positions and, when the sections are connected by screwing one upon the other, it frequently happens that the tubular fixtures are not cut with sufficient accuracy to allow the inclosing shells to be properly adjusted or when the

shells are made of semi-spherical or similar sections adapted to fit one within the other, the adjustment of the imperfectly cut threaded parts one upon the other in securing them in place is more or less liable to buckle one of the shell sections to such an extent as to make it practically impossible to assemble the other shell section thereon. Many of these fixture arms are curved more or less and adapted to be brought to a predetermined position for use and, after screwing them tightly into the head as they should be, they are frequently deflected from their proper positions and when so adjusted are loose and liable to jar out of place.

The main object, therefore, of my invention is to overcome these difficulties by providing slip connections between the fixture and its supporting head so that they may be accurately adjusted to any desired position and held in fixed relation without rotating or turning the lamp-supporting arms.

Another object is to reduce the cost of manufacture and to render the operation of assembling the fixtures more expeditious, economical and accurate without liability of stripping the insulation from the wires or deforming the canopies or protective casings which surround the coupling.

Other objects and uses will be brought out in the following description.

In the drawings, Figure 1 is a side elevation of one form of my invention as applied to drop fixtures showing the inclosing case in section. Fig. 2 is a top plan, partly in section, of the same device in which the spherical case is also shown in section. Fig. 3 is an enlarged vertical sectional view of the coupling head for the fixtures shown in Figs. 1 and 2. Fig. 4 is an enlarged transverse sectional view through one of the friction clamps taken on line 4—4, Fig. 2.

The drop fixture shown in Figs. 1, 2 and 3, comprises a tubular conduit —1— having its lower end provided with a head —2— screwed or otherwise secured thereon and provided with a plurality of, in this instance three, tubular sockets —3— radiating therefrom and divided through one side at —4— for receiving a corresponding number of tubular lamp fixtures —5—.

The split sides of the tubular hubs —3— are provided with laterally projecting ears —6— having registering apertures, one of which is threaded, for receiving clamping screws —7— by which the split hubs may

be compressed into frictional engagement with the adjacent ends of the lamp fixtures —5— for holding the latter in fixed relation to the head.

- 5 The upright tubular conduit —1— may be attached at its upper end to any suitable ceiling fixture, not necessary to herein illustrate or describe, but is adapted to receive electric feed wires —8— which are drawn 10 or threaded through the tube —1— so as to extend into and through the head —2—. For this purpose, the head —2— is provided at its junction with the hubs —3— with outlet openings —9— for the ends of the 15 wires to facilitate the connections of the feed wires with additional wires —9'— which are drawn or threaded through the lamp fixtures —5— previous to their insertion into their respective sockets —3—.
- 20 The inner ends of the lamp-supporting arms or fixtures —5— are fitted with an easy sliding fit in the hubs or sockets —3— when the screws —7— are loosened, thereby establishing a sliding engagement between 25 said lamp fixtures and head so that the fixtures may be adjusted by endwise sliding movement to any desired position and firmly held in such position by the tightening of the screws —7— which compress the 30 corresponding hubs upon the adjacent ends of the fixtures —5— and firmly hold them in operative position, thereby avoiding any necessity for turning and consequently reducing the liability of stripping the insulation on the wires or of straining the terminal connections of said wires with the lamp 35 sockets or with the feed wires —8— and also avoids any liability of buckling or deforming portions of the protective hood or 40 casing as —a— through which the lamp fixtures extend.

The heads of the screws —7— and also the openings —9— are preferably on the underside of the head —2— where they are 45 easily accessible for clamping the lamp fixtures and also for attaching the ends of the feed wires to those which are passed through the lamp-supporting arms, it being understood that the casing —a— is preferably made in sections so that the lower section 50 may be removed by unscrewing a suitable nut —b— on the lower end of a pendant rod —c— which is centrally screwed into the underside of the rod —2— and extends

downwardly through an opening in the 55 lower section of the casing.

The central portion of the head —2— is provided with a threaded socket —10— for engaging the lower threaded end of the upright tube —1—, thereby establishing a 60 positive connection between the head and its supporting tube.

The radial hubs or sockets —3— are preferably spaced uniform distances apart and the inner ends of their lower sides are 65 spaced apart from the main body to form the openings —9— through which the ends of the wires are drawn in electrically connecting them one to the other.

What I claim is:

1. An electric light fixture comprising a head having a central chamber and radially projecting split hubs spaced apart circumferentially and provided with apertured ears projecting into such spaces, the upper 75 ear being of greater cross sectional area than the lower ear and extending beneath the horizontal axis of the hub, lamp-supporting arms slidably engaged in said hubs, with the enlarged upper ear engaging the 80 same entirely over its adjacent face and below the transverse axis of the arm, and bolts passed through the apertured ears for tightening the hubs on the arms.

2. An electric light fixture comprising a 85 head having a central chamber and radially projecting split hubs spaced apart circumferentially and provided with apertured ears projecting into such spaces, lamp supporting arms slidably engaged in said hubs, 90 one of said ears of each pair being formed to have the inner end thereof engage the arm throughout its length and past the transverse axis thereof, bolts passed through 95 the apertured ears for tightening the hubs on the arms, the portions of the hub between the arms being extended and united at points above and below the plane of the hubs and provided with co-axial threaded sockets, a supporting pipe screwed in the 100 upper socket, and a case-supporting rod secured in the lower socket.

In witness whereof I have hereunto set my hand this 25th day of September, 1913.

CYRIL W. KING.
